UNITED STATES PATENT OFFICE

107,785

DESIGN FOR A MICROPHONE CONTROL

Aston L. Moore, South Bend, Ind., assignor to
Cin-Rad Corporation, Chicago, Ill.

Application April 9, 1937, Serial No. 68,646

Term of patent 7 years

To all whom it may concern:

Be it known that I, Aston L. Moore, a citizen of the United States, residing at 1046 No. Lauderdale Avenue, South Bend, Indiana, have invented a new, original, and ornamental Design for Microphone Control, of which the following is a specification, reference being had to the accompanying drawing forming part thereof, in which the figure

is a front perspective view of a microphone control showing my new design. The rear portion of the microphone control is plain.

I claim:

The ornamental design for a microphone control, substantially as shown and described.

ASTON L. MOORE.
